UNITED STATES PATENT OFFICE.

CLIFFORD G. KING, OF PROVIDENCE, RHODE ISLAND.

BROOCH.

1,023,940.

Specification of Letters Patent.

Patented Apr. 23, 1912.

Application filed July 20, 1911. Serial No. 639,566.

To all whom it may concern:

Be it known that I, CLIFFORD G. KING, a citizen of the United States, and a resident of Providence, in the county of Providence and State of Rhode Island, have invented 5 a new and useful Improvement in Brooches, of which the following is a specification.

My invention relates to brooches or similar pins and particularly to the so called 10 "beauty" or "baby" pins, and its object is to improve the construction thereof in the manner hereinafter set forth.

The drawings which accompany and form 15 a part of this specification illustrate one embodiment of my invention.

In the drawings, Figure 1 is a side view of a pin embodying my invention; Fig. 2 is a plan view of the same; Fig. 3 is a longitudinal section, and Figs. 4 and 5 represent 20 blanks from which the back plate and pin respectively may be formed.

In the particular drawings selected for illustrating my invention, 1 represents the front or ornamental plate, the edge of which 25 is rolled over to form a continuous flange or bead 2 engaging the back plate 3. The back plate preferably is constructed from the blank shown in Fig. 4. The blank is provided with two transverse slots 6 and 7 ar- 30 ranged as shown near the ends of the blank and one end thereof is provided with a longitudinal slot 8. The projecting member 4 on the other end is bent at right angles to the blank to form a catch or keeper for the 35 pin point, and the ear 5 may be bent backward against the back plate in the opposite direction from the catch 4 in order to retain the flattened end 12 of the pin as herein- 40 after more fully explained. The pin tongue may conveniently be formed from a blank such as shown in Fig. 5, and consists of the 45 stem portion 10, the flattened spring portion 11, and the flattened end portion 12. The spring portion of the pin tongue pref- erably is corrugated as shown at 13. When 50 the blank is placed in a suitable press to form the pin-retaining lug 5 and the catch 4, that portion thereof between the slot 7 and the slot 8 is raised above the plane of the back plate so as to form the bridge 9, shown in Figs. 2 and 3. When the back

plate and pin have been suitably formed, the end 12 of the latter is inserted in the slot 8 and up through the slot 7, and then is passed through the slot 6 until the flattened 55 end portion 12 lies flat along the under portion of the back plate as shown in Fig. 2. The lug 5 is then pressed down on said flattened portion, the back plate inserted in the front plate 1 and the edge of the latter 60 rolled over to retain the same as shown in Fig. 2.

It will be seen that by means of the construction hereinafter described, I am able 65 to provide a pin, the parts of which may be inexpensively assembled without solder, and which when once assembled cannot be disengaged by ordinary usage. It will be obvious that the corrugation of the spring 70 portion of the pin tongue greatly increases the flexibility thereof and also greatly increases the security of engagement with the fabric to which the pin is applied. It will be noted also that greater elasticity is secured by the free movement with respect 75 to the back-plate slots 7 and 8 of that portion of the pin-tongue which lies under the raised bridge 9.

It will be understood that while I have 80 described one embodiment of my invention with some particularity, nevertheless various modifications within the scope of the appended claims may be made in the particular form shown and described without departing from the spirit of my invention. 85

I claim:

1. In a pin, a pin tongue formed of wire pointed at one end, intermediately bent upon itself, and having its other end flattened in a plane transverse to that of said 90 bending, said flattened portion being provided with corrugations.

2. In a pin, a back plate provided with a slot at one end thereof, a transverse slot near each end of said back plate, a pin 95 tongue having a flattened portion threaded through said slots, and means for binding the forward end of said flattened portion to said back plate.

3. In a pin, a back plate provided with an 100 end slot and a transverse slot near each end thereof, a raised bridge formed between one

of said transverse slots and said end slot, a pin tongue having a flattened portion passing under said bridge and through the other of said transverse slots and means for binding the forward end of said flattened portion to said back plate.

In testimony whereof, I have hereunto

subscribed my name this 13th day of July, 1911.

CLIFFORD G. KING.
